UNITED STATES PATENT OFFICE.

BRANDT V. B. DIXON, OF ST. LOUIS, MISSOURI, ASSIGNOR OF ONE-HALF TO
AMOS F. HOFFER AND JOHN H. LAWRENCE, BOTH OF SAME PLACE.

CHILD'S CARRIAGE.

SPECIFICATION forming part of Letters Patent No. 296,149, dated April 1, 1884.

Application filed December 14, 1883. (No model.)

To all whom it may concern:

Be it known that I, BRANDT V. B. DIXON, of St. Louis, Missouri, have made a new and useful Improvement in Children's Carriages, of which the following is a full, clear, and exact description, reference being had to the annexed drawings, making part of this specification, in which—

Figure 1 is a view in perspective of a carriage-body having the improvement; Fig. 2, a vertical longitudinal section of the body, the section being just within the near side piece of the movable head or end; Fig. 3, a similar section, the end being turned up; Fig. 4, a section on the line 4 4 of Fig. 3; Fig. 5, a section on the line 5 5 of Fig. 2; and Fig. 6 a vertical section showing the clamp in position. The last three named views are upon an enlarged scale.

20 The same letters of reference denote the same parts.

This invention is an improvement in that class of children's carriages which have the head or end of the carriage-body movable, to be turned or down, as desired.

25 The improvement relates to the mode of constructing and attaching the movable parts, to the adjustable head-board, which, when down, closes the end of the body, and to the means for bracing and tying the head-board, and to the combination of the various parts.

30 A represents the body of a child's carriage having the improvement in question. Aside from its improved features, the body may be of any of the usual descriptions. The movable portion of the body consists of the part B, which is hinged at b b to the main portion of the carriage-body, of the part C, which is hinged at c c to the part B, and of the side pieces, D D, which are secured to and move with the part B. This movable portion is adapted to be turned upon the hinges b b upward into the position shown in Figs. 1, 3, or turned downward into the position shown in Fig. 2.

35 40 45 When it is upturned, the parts B C form the end of the carriage-body, and constitute a back against which the child may rest. When the movable portion is turned down, the part C forms the end board of the carriage-body.

50 The movable portion of the body can be secured in either of the positions described, or

in any intermediate position, in the following manner:

The sides E E of the carriage-body are extended or constructed so as to form a curved edge, e e. These edges e e correspond in shape and coincide with the general curvature of the edges d d of the side pieces, D D. The edges d d are notched, waved, corrugated, or scalloped, substantially as shown. A clamp, F, 60 consisting of the brackets f and the set-screw f', is attached to each of the parts E E, as indicated in Fig. 1. The point of the set-screw f' is adapted to be screwed down upon the waved edge d of the side piece, D, and, by 65 tightening the set-screw against the edge d, the side piece, D, is locked. Therefore, to operate the improvement, the set-screws f' are loosened and the movable portion of the carriage-body turned upward or downward, as 70 desired, and when in the desired position the set-screws are tightened.

The parts G G are used both as a brace and as a tie. They consist of rods jointed at g g to the fixed portion of the carriage-body, and at g' g' to the head-board C. In the upright position of the movable portion shown in Figs. 1, 3, they serve more especially as braces to support the parts B C, and to more effectually support the part C the braces at g' g' are shaped to form 80 an extended bearing against the head-board C. When the movable portion of the carriage-body is turned down, as in Fig. 2, the parts G G serve to tie the head-board C. The parts G G also serve to turn the board C properly 85 into position as the movable portion of the body is turned upward and downward. The side pieces, D D, at d' d', are shaped to enable the board C to be turned upward against them, and thereby close the body at its corners, when the 90 movable portion of the body is turned down. The preferable modes of connecting the bars G G with the head-board C and the fixed portion of the carriage-body are shown in Figs. 4 and 5, respectively. The side pieces, D D, 95 serve also to close the sides of the body when the movable portion is turned down.

I claim—

1. The combination of the part B, the part C, and the rods G G with the fixed part of 100 the carriage-body A.
2. The combination of the part B, the part

C, the side pieces, D D, and the rods G G with the fixed part of the carriage-body A, as described.

3. The combination, in the carriage-body A, of the hinged part C and the rods G G, as described.

4. The combination, in the carriage-body A, of the parts B C, the side pieces, D D, the

sides E E, having the parts e e, the clamps F F, and the rods G G, as described.

Witness my hand this 10th December, 1883.

BRANDT V. B. DIXON.
